ADJUSTABLE ELECTRIC LAMP

Clarence Birdseye, Gloucester, Mass., assignor to
 Birdseye Electric Corporation, Dover, Del., a
 corporation of Delaware

Application November 2, 1936, Serial No. 108,786

14 Claims. (Cl. 176—32)

This invention relates to electric lamps and particularly to those which employ in their structure a bulb carrying a reflecting surface for concentrating and directing the light from the lamp into a definite beam or field. In one aspect the invention comprises a base having the usual socket-fitting end portion together with an intermediate section which is flexible to the extent of permitting the position of the bulb to be 5 angularly adjusted with respect to the socket-fitting portion of the base. A lamp of this construction may be secured or otherwise fixed in an already-installed socket of any commercial construction and then adjusted either angularly or longitudinally so that the light emitted thereby shall be distributed most favorably for the requirements of the individual situation.

It is, of course, possible to install commercial sockets at any desired angle or to provide such 20 sockets with external reflectors directing the field or beam of light in any desired direction, but when such an installation has been made, it is inflexible and the light distribution cannot easily be changed to accommodate different requirements. For example, an installation may be 25 made with the object of illuminating with the greatest intensity one end of the space in a show window, whereas conditions may change so that it becomes desirable to concentrate the light of 30 the installation upon the center of the window space or along its rear wall or to create a spot-light effect. In the present conditions such a change can be effected only by repositioning the sockets or providing a new set of external reflectors. The present invention provides an 35 integral lamp structure adapted for any commercial socket and makes provision for the easy angular adjustment and readjustment of the lamp with its reflecting surfaces to secure the 40 desired distribution of its light.

The lamp of my invention is also particularly 45 useful in accommodating separate external reflectors which have been already installed, in that its construction facilitates and permits adjusting the lamps properly with respect to the focus of the reflectors. This may require a longitudinal or height-wise adjustment of the lamp with or without an angular adjustment and all such adjustments are within the range of movement 50 permitted by the flexible section of the base herein disclosed.

The mechanical construction of the flexible portion of the base of my invention may take 55 various forms. Satisfactory results may be secured by elongating a hollow metal base of com-

mercial construction sufficiently to include a corrugated or bellows section of copper or other easily flexed metal, or the base may be constructed to include a helix of non-resilient flexible wire, or a universal joint may be otherwise incorporated in the base in a location between its socket-fitting end portion and the portion thereof which is united to the glass of the bulb. 5

My invention includes within its scope not only the complete electric lamp structure including a base by which angular adjustment of the bulb may be effected, but it also includes the novel base herein shown per se.

As an additional feature my invention contemplates a base having a flexible section through 15 which one or more lead wires may be conducted and which have insulating protection, so that in flexing the base in adjusting the position of the bulb there will be no danger of short-circuiting the lead wire upon the inner walls of the 20 base. Further, in bases wherein one of the lead wires is secured within the socket-fitting portion of the base it is contemplated that the lead wire will be flexible and have provision for extension or elongation to guard against danger of breaking the lead wire in making any desired adjustment of the bulb position. 25

These and other features of the invention will be best understood and appreciated from the following description of two preferred embodiments selected for purposes of illustration and shown in the accompanying drawings in which,—

Fig. 1 is a view in elevation, partly in section, 30 of an incandescent lamp equipped with a base of my invention.

Fig. 2 is a similar fragmentary view showing a portion of the bulb in an angularly adjusted position.

Fig. 3 is a fragmentary view in elevation, partly 35 in section, showing a modified form of base,

Fig. 4 is a view in elevation, partly in section, 40 of an incandescent lamp having a modified form of base,

Fig. 5 is a fragmentary view showing the base 45 elongated, and

Fig. 6 is an enlarged view of a base of modified construction.

Figure 7 is a sectional detail of the form shown in Figure 5; and

Figure 8 is a section similar to Figure 7, of the 50 structure shown in Figure 6.

The bulb 10 herein shown may be of any usual or commercial construction equipped with an internal reflecting surface or a separate reflector to concentrate and define the beam of light 55

emitted by the filament, not shown, or other light source within the bulb. For example, the bulb may be provided as shown in Fig. 1 with an internal coating of metallic silver extending from the line of maximum bulb diameter to a line in the neck of the bulb, acting to hood the filament and direct the light of the lamp outwardly in a concentrated beam through the bowl of the bulb. The bulb includes the usual glass mount 11 which is sealed into its neck and which supports the filament structure. The upper end of the mount 11 constitutes a solid press 12 in which are embodied the two lead wires 13 and 14. An exhaust tube 17 of usual construction is shown as located within the mount 11, this having been sealed at its lower end when the bulb was exhausted in the process of manufacturing the lamp.

The base shown in Fig. 1 comprises three portions having distinct functions. First, the usual threaded, socket-fitting end portion 20, second, the flexible corrugated intermediate portion 21, and third, the sleeve portion 22 which fits the glass neck of the bulb. The end threaded portion 20 is substantially rigid in its construction and may comprise sheet brass or the like molded or spun to present an external thread to be received in a socket. The intermediate or bellows portion 21 may be constructed of a softer and more flexible metal such as copper and is shaped to include two or more rounded corrugations of the general construction employed in metallic bellows. The flexible section 21, instead of being of dissimilar metal, may be of the same metal as the threaded end portion 20 but annealed so that it is softened and rendered flexible. The upper end of the base comprises a sleeve portion 22 which is shaped to surround the tapering end of the neck of the bulb and to contain a quantity of adhesive cement 23. Preferably and as herein shown the end of the bulb neck may be provided with depressions or indentations 16 which provide anchorage for the cement 23. In any case the function of the upper portion of the base 22 is to form a fast and reliable union with the glass neck of the bulb. In addition to its flexing function the bellows section 21 provides an efficient radiator for dissipating heat from the lamp, a useful characteristic particularly in high wattage lamps.

One of the lead wires 13 is bent about the lower end or flange of the mount 11, brought out in the sleeve portion 22 of the base and united to the edge thereof by a drop of solder 15. The other lead wire 14 is brought down through the hollow base and connected to a metallic button 25 which is insulated from the rest of the base in the usual manner. It is important to insulate the lead wire 14 within the base so that it cannot be moved into contact with the inner wall of the base when the section 21 is flexed. For this purpose the lead wire 14 is shown as encased in an insulating tube 24 from a point adjacent to the lower end of the mount 11 to a point adjacent its connection with the button 25, or in other words, for substantially the entire length of the base. Any suitable form of insulating protection adequate to prevent short circuiting of the lead wire against the base may be employed, such as tubing or beads of ceramic material, asbestos, glass, or the like. It is also to be noted that the insulated portion of the lead wire 14 may be coiled into the form of a loose helix or spring and thus provision is made for the ex-

tension of the lead wire which is called for when the base is flexed.

As the lamp is initially constructed and distributed for use the base is symmetrically and concentrically disposed with reference to the axis 5 of the bulb as shown in Fig. 1 and the lamp may thus be screwed into any socket without special attention or consideration of any kind. Having once fixed the lamp in its socket any desired angular adjustment may now be secured by merely bending or tipping the bulb in the desired direction, as for example, as suggested in Fig. 2. Under these circumstances the corrugations of the flexible portion 21 are contracted on one side of the base and expanded on the other side, and an angular relation is established between the threaded end portion of the base and its sleeve portion 22, together with the bulb and all the parts carried thereby. As already noted, the section 21 is non-resilient although flexible, so that 20 it will readily assume any adjusted position and when once adjusted will maintain that position indefinitely. However, should further and different adjustment be desired this may be secured by merely bending or tipping the bulb in the 25 desired direction.

One of many alternative constructions is illustrated in Fig. 3 in which is shown a base having a threaded end 30 and sleeve portions 32 of the character already described, but which portions 30 are united to an intermediate portion or section 31 comprising a helix of flexible non-resilient wire. The helix illustrated comprises approximately five turns flattened at both ends and united by soldering or brazing to the upper and 35 lower ends respectively of the sections 30 and 32. The lead wire 14 which extends down through the base is connected to the metal button 35 and provided with an insulating tube 34 as described in connection with Fig. 1. The action of the base 40 shown in Fig. 3 is similar to the action of the base already described. It may be inserted readily in any socket, and then the bulb may be angularly adjusted by flexing the turns of the helix in the section 31 of the base. The wire of 45 the portion 31 of the base is shown in Fig. 3 as being circular in cross-section, but this may be flattened or otherwise modified if desired.

In Figs. 4 and 5 is shown a clear glass bulb 40 having a modified form of base. In this construction the bulb 40 is provided with the usual mount 41 terminating in a press 42 in which are embedded lead wires 43 and 44 and having a sealed exhaust tube 47. The hollow metallic base comprises a rigid portion 50 threaded to fit 55 the usual commercial socket, a flexible intermediate bellows portion 51 and a flaring sleeve portion 52 which is united to the end of the neck of the bulb by cement 53. To supply a firm anchorage for the cement the neck of the bulb 60 is provided with depressions or indentations 46. The lead wire 43 is conducted out through one side of the sleeve portion 52 and secured by a drop of solder as usual. The flexible bellows portion 51 is herein shown as comprising four deep 65 corrugations, these being formed of copper or other flexible metal. In this instance the entire outer surface of the bellows section 51 is covered with a thick coat of flexible bakelite varnish 56, thus insulating this portion of the base externally.

The lead wire 44 is conducted to the bottom of the base where it is soldered to the button 55. The portion of this lead wire which passes through the base is shown as coiled in a helix

and provided with an insulating cover 54 of woven asbestos or other insulating fabric. Its function is to prevent the lead wire from being short-circuited against the interior of the base 5 when the portion 51 is flexed in adjusting the lamp. Provision is also made for preventing the lead wire from becoming wound about the exhaust tube 47 in continued flexing of the base. To this end a fibre washer 56 is threaded upon 10 the end of the exhaust tube 47 and provided at one side with a passage for the insulated lead wire 44. It will be seen that the washer 56 acts as a spacer for the lead wire, keeping it concentrically at a fixed distance from the tube 15 however the bellows portion 51 of the base may be flexed.

In Fig. 5 the lamp of Fig. 4 is shown as adjusted longitudinally or height-wise with respect to the socket-fitting portion 50 by means of a 20 symmetrical elongation or expansion of the corrugations of this portion. As already noted this adjustment is useful in bringing the lamp to the focus of an external reflector already installed and this longitudinal adjustment may be 25 combined or not with an angular adjustment as desired.

In some cases it may be desirable to insulate the flexible section of the base from its socket-fitting end and such a construction is illustrated 30 on a large scale in Fig. 6. In this construction the base comprises a rigid threaded portion 60 having the usual insulated button 61 at its lower end. The flexible bellows portion 63 and the sleeve portion 64 are formed in one piece and 35 connected to the threaded socket-fitting portion 60 through the medium of an insulating ring 62 of fibre or the like. The ring 62 is of sufficient width so that the threaded portion 60 of the base may be connected thereto by one set of 40 rivets while the flexible bellows portion 63 is connected thereto by a separate series of rivets. Accordingly, there is no electrical connection between these two portions of the base and the 45 flexible portion remains dead. The lead wires 65 and 67 in this construction are provided with flexible insulating tubes 66 of asbestos or the like. The lead wire 65 is conducted to the button 61 and soldered thereto, whereas the lead wire 67 is conducted out between the flange of 50 the threaded portion 60 and the insulating sleeve 62 and soldered to the socket-fitting portion of the base by a drop of solder 68. As in the base of Figs. 1 and 2 the base shown in Figs. 4 and 5 with its flexible section forms as a whole a closed 55 tubular structure completely enclosing and protecting the end of the bulb neck and the lead wires emerging therefrom.

As already intimated mechanical joints may be substituted if desired for the flexible portion 60 or section of the base in such manner as to provide for the desired universal angular adjustment of the bulb with respect to the socket-fitting end of the base.

Having thus described my invention, what I 65 claim as new and desire to secure by Letters Patent of the United States, is:—

1. An electric reflector lamp designed to concentrate its light output into a predetermined field, having a bulb and a base including a rigid portion shaped to fit into a socket and a readily adjustable non-resilient flexible portion interposed between the bulb and said rigid portion, whereby the lamp is given capacity for sustained angular adjustment with respect to its socket.

2. An electric reflector lamp designed to con-

centrate its light output into a predetermined field, having a bulb and a metallic base including a rigid socket-fitting portion, a sleeve portion fitting the neck of the bulb, and a closed tubular intermediate section which is flexible and non- 5 resilient.

3. An electric reflector lamp having an adjustable bulb, and an integral metallic base having a sleeve portion fitted to the neck of the bulb, a rigid threaded end portion, and an intermediate 10 flexible portion comprising a plurality of corrugations readily deformable in adjusting the bulb.

4. An electric lamp having a bulb containing a light source, a metallic base having a socket-fitting portion initially disposed symmetrically 15 with respect to the axis of the bulb, and a closed tubular, non-resilient and flexible section which when flexed to position the bulb at an angle to said socket-fitting portion, serves to maintain the bulb in such position of angular adjustment, and 20 a lead wire having insulating protection within the base.

5. An electric lamp having a reflecting bulb containing a light source, a metallic base having a rigid threaded end and an intermediate portion 25 of flexible, non-resilient corrugations, and an insulated extensible lead wire secured in said threaded end.

6. An electric lamp having a bulb containing a light source, and a base including in its structure 30 a rigid, socket-fitting end, and an intermediate bellows section composed of non-resilient flexible corrugations of greater external diameter than that of said socket-fitting end.

7. An electric reflector lamp having a bulb 35 containing a light source, a hollow metallic base having a threaded end and an intermediate non-resilient flexible section, a mount sealed into the neck of the bulb, a lead wire extending through the mount and being secured in the end of the 40 base, and an insulating tube surrounding the lead wire within the base to prevent it from contacting the base when the latter is flexed.

8. An electric reflector lamp having a bulb containing a light source, and a metallic base 45 having a socket-fitting end, and an intermediate portion comprising a non-resilient flexible close wound, permanently deformable helix of non-re-

silient wire.

9. A high wattage electric lamp having a bulb 50 containing a light source, and a metallic base including in its structure a rigid end portion shaped to be substantially enclosed within a socket, and an intermediate flexible section so located as to be disposed outside the socket and 55 having deep corrugations formed therein to facilitate heat radiation and give angular adjustment of the lamp with respect to its socket.

10. An electric lamp having a bulb containing a filament mount, lead wires and an exhaust 60 tube sealed therein, and having a base with a non-resilient flexible section therein giving capacity for angular adjustment to the lamp, and means within the base to prevent the lead wires from becoming entangled with the end of the 65 exhaust tube.

11. An electric lamp having an adjustable bulb containing a filament mount, lead wires and an exhaust tube sealed in the mount, and a base with a flexible section therein giving adjustability to the lamp, and an insulating washer disposed concentrically about said tube and maintaining said lead wire in spaced relation with respect to said tube in all adjusted positions of the lamp.

12. An electric lamp having a bulb containing a light source, and a base including in its structure a rigid, socket-fitting portion, and an intermediate bellows portion composed of flexible metal corrugations having an external coating of flexible insulating material.

13. An electric lamp having a bulb containing a light source, and a base including in its structure a metallic socket-fitting portion, and an exposed bellows portion of flexible corrugations mechanically connected to the socket-fitting por-

tion, electrically insulated therefrom and angularly adjustable with respect thereto.

14. An adjustable base for an incandescent electric lamp comprising a socket-fitting end portion having an insulating ring connected thereto, and a bulb-fitting portion connected to said insulating ring and insulated thereby from said end portion, the bulb-fitting portion including a flexible bellows section giving relative angular adjustment of said two portions of the base. 10

CLARENCE BIRDSEYE.
